S. A. STONEBACK.

RAILROAD TIE.

APPLICATION FILED JAN. 13, 1913.

1,072,053.

Patented Sept. 2, 1913.

UNITED STATES PATENT OFFICE.

SAMUEL A. STONEBACK, OF PHILADELPHIA, PENNSYLVANIA.

RAILROAD-TIE.

1,072,053.

Specification of Letters Patent.

Patented Sept. 2, 1913.

Application filed January 13, 1913. Serial No. 741,770.

To all whom it may concern:

Be it known that I, SAMUEL A. STONEBACK, a citizen of the United States, residing at Philadelphia, in the county of Philadelphia and State of Pennsylvania, have invented certain new and useful Improvements in Railroad-Ties, of which the following is a specification.

My invention relates to improvements in railroad ties, the object of the invention being to provide an improved tie composed of concrete or other composition including cement, sand, and the like having an arrangement of embedded blocks of wood, and which permit a cushioning effect and allow of a certain amount of elastic movement of the tie within a limit restricted by the elasticity of reinforcing rods.

A further object is to provide a tie of this character which is composed of a plurality of sections held together by reinforcing rods and locate at the juncture points, blocks of wood which act as cushions to take up jar and vibration due to the passage of rolling stock over the road.

A further object is to provide in a tie of the character set forth, an improved arrangement of rail supporting blocks and rail securing means.

30 A further object is to provide an improved construction of concrete tie having cushioning blocks inserted in the tie adjacent the ends thereof and upon which the rails are secured, and provide between the 35 ends of the tie, cushioning blocks which are located at breaking points or between sections of the tie, the latter being held together by reinforcing rods.

With these and other objects in view, the 40 invention consists in certain novel features of construction and combinations and arrangements of parts as will be more fully hereinafter described and pointed out in the claims.

45 In the accompanying drawings: Figure 1 is a plan view illustrating my improvements. Fig. 2 is a view in longitudinal section on the line 2—2 of Fig. 1. Fig. 3 is a view in longitudinal section illustrating 50 a modified form of tie, a section being taken directly through the center of the tie, but showing the central reinforcing rod in elevation. Fig. 4 is a view in section on the line 4—4 of Fig. 2. Fig. 5 is a view in section on the line 5—5 of Fig. 2. Fig. 6 is a 55 broken view in elevation of one of the rail

securing bolts, and Fig. 7 is a perspective view on an enlarged scale of one of the bolt engaging anchor plates.

My improved tie is constructed of any 60 approved concrete composition, and I would have it understood that in the use of this term "concrete", I employ it in its broadest possible sense to include any composition which when it becomes set, forms an artificial stone or like tie, preferably one in which cement is largely used in combination with sand, etc.

The tie 1 is of any dimension in accordance with the requirements of the trade, 70 and is provided with a plurality of reinforcing rods 2 and 3. These rods are given different reference characters because they differ in form. I have shown as a preferable form, two of the rods 2, and one rod 75 3, the latter being located between the rods 2, 2.

In the upper face of the tie, adjacent its ends, dove-tailed blocks of wood or other similar material 4, are embedded in the tie. 80 As a matter of fact, the recesses are formed in the tie, and the blocks are driven into the tie sidewise, and are preferably coated with coal tar so as to preserve them from the weather, and to more securely bind them in 85 the tie. It will be noted that the rods 2, 2, arch downwardly below the blocks 4, 4, and the ends of the rods 2, as well as the ends of the rods 3, project downwardly as indicated at 5 to prevent any possibility of longitudinal movement of the rods in the tie. 90 Ths rods 3 are appreciably shorter than the rods 2, and are located between the blocks 4, 4, only, while the longer rods extend beyond the rails and due to their 95 arched formation, strengthen the portion of the tie below the blocks and sustain the necessary weight to which such blocks are subjected by the passage of rolling stock over the tracks. Anchor plates 6 are embedded 100 in the concrete below the rods 2, 2, and below the blocks 4. These anchor plates have recessed ends 7 to receive the rods 2, and are provided centrally with screw-threaded 105 openings 8 to receive the threaded ends of rail locking bolts 9.

In forming the tie, bolts similar to bolts 9 are positioned in the mold and after the tie is molded, they are withdrawn so that suitable openings are provided in the tie for 110 the reception of the bolts 9. The blocks 4 are provided with openings to register with

the openings in the tie, so that the bolts may be readily operated. The rails 10, 10 are located on blocks 4, and are secured by means of the bolts 9. These bolts 9 have enlarged heads 11 which gradually taper into the longitudinal portion of the bolt, and are adapted to fit over the tread portions of the rail. Angular wrench receiving enlargements 12 are formed on the extreme ends of bolts 9, so that when said bolts are turned, their heads 11 will be moved into locking engagement with the rail base flanges. The rails are therefore rigidly secured on the upper surface of the blocks 4, and are held against possibility of movement by reason of their engagement with the anchor plates 8. In the event one of these anchor plates should become useless for any cause, the tie could be repaired by breaking away the concrete at the bottom, inserting a new anchor plate, and then filling the same with composition. Each tie between the rail supporting blocks 4 is provided in its lower face with one or more dove-tailed recesses 13 to receive blocks 14 preferably of wood which are dove-tailed to conform to the shape of the recesses and are driven into the recesses and preferably coated with pitch.

In Fig. 2 I have illustrated a tie with a single block 14 located centrally between the ends of the tie. In Fig. 3 I have shown two blocks 14 which are located at opposite sides of the center of the tie. In both forms, it will be noted that I have separated the tie sections above the blocks 14 as indicated at 15. These spaces 15 are preferably filled with coal tar, so that water cannot pass through the same, and contact with the reinforcing rods or with the blocks 14.

My improved tie in operation is designed to cushion the jars and vibrations and take the place of ordinary wooden ties, yet I construct the ties largely of concrete.

With my improvements, the weight of the rolling stock on the rails will necessarily cause the ends of the rail to go downwardly, which tends to draw the upper part of the tie apart where it is positioned over the block or blocks 14.

The reinforcing rods 2 elastically resist this action, and the blocks 14 cushion such a tendency. Hence, vibrations are consumed by the blocks 14, and blows of direct impact are consumed by the blocks 4. This double set of blocks, namely, the blocks 4 below the rails, and the blocks 14 between the ends of the tie, consume the jars and vibrations to which the tie is subjected, and permit the rest of the tie to be composed of reinforced concrete or other suitable composition.

Various slight changes might be made in the general form and arrangement of parts described without departing from my in-

vention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A tie comprising two sections, a cushioning block between the sections, and devices above the cushioning blocks elastically tying the sections together, substantially as described. 70
2. In combination with a concrete tie, a block inserted in the lower face of the tie between the ends of the latter and devices above the block connecting the tie sections, substantially as described. 75
3. In combination with a concrete tie, a block inserted in the lower face of the tie between the ends of the latter, and reinforcing rods in the tie above the block, substantially as described. 80
4. In combination with a concrete tie, a block inserted in the lower face of the tie between the ends of the latter, reinforcing rods in the tie above the block, and said tie broken apart above said block, substantially as described. 85
5. In combination with a concrete tie composed of a plurality of sections, rods embedded in the ties and connecting the sections, and blocks inserted in the recesses in the tie formed at the meeting ends of said sections, said blocks located out of alignment with the rods, substantially as described. 90
6. The combination with a concrete tie, two rail supporting blocks in the upper face of the tie, a block in the lower face of the tie and devices above the last-mentioned block connecting the tie at both sides of the block, substantially as described. 95
7. The combination with a concrete tie, two rail supporting blocks in the upper face of the tie, a block in the lower face of the tie, and reinforcing rods in the tie positioned below the first-mentioned blocks and above the last-mentioned blocks, substantially as described. 100
8. In combination with a concrete tie having recesses in its upper face adjacent its ends, and a recess in its lower face between its ends, blocks inserted in said recesses, devices anchored in the tie and extending across the tie out of alignment with the said recesses, and means for securing rails on said first-mentioned blocks, substantially as described. 105
9. In combination with a rail having dove-tailed recesses in its upper face adjacent its ends, and a dove-tailed recess in its lower face between its ends, dove-tailed blocks located in said recesses, reinforcing rods embedded in the concrete tie and 110
10. In combination with a rail having dove-tailed recesses in its upper face adjacent its ends, and a dove-tailed recess in its lower face between its ends, dove-tailed blocks located in said recesses, reinforcing rods embedded in the concrete tie and 115
11. In combination with a rail having dove-tailed recesses in its upper face adjacent its ends, and a dove-tailed recess in its lower face between its ends, dove-tailed blocks located in said recesses, reinforcing rods embedded in the concrete tie and 120
12. In combination with a rail having dove-tailed recesses in its upper face adjacent its ends, and a dove-tailed recess in its lower face between its ends, dove-tailed blocks located in said recesses, reinforcing rods embedded in the concrete tie and 125
13. In combination with a rail having dove-tailed recesses in its upper face adjacent its ends, and a dove-tailed recess in its lower face between its ends, dove-tailed blocks located in said recesses, reinforcing rods embedded in the concrete tie and 130

located below the first-mentioned blocks and above the last-mentioned blocks, substantially as described.

10. In combination with a concrete tie 5 having recesses in its upper face adjacent its ends, and a recess in its lower face between its ends, blocks in said recesses, reinforcing rods embedded in the tie, positioned above the last-mentioned block and below the first- 10 mentioned blocks, and said reinforcing rods

bent at an angle at their ends, substantially as described.

In testimony whereof I have signed my name to this specification in the presence of two subscribing witnesses.

SAMUEL A. STONEBACK.
